DESIGN FOR A SADIRON COVER

Percy William Davis, Broadwell, Oldbury, England, assignor to Simplex Electric Company Limited, Broadwell, Oldbury, England

Application October 3, 1939, Serial No. 87,491
In Great Britain June 22, 1939

Term of patent 3½ years

To all whom it may concern:

Be it known that I, Percy William Davis, a subject of the King of Great Britain and residing at Broadwell Road, Broadwell, Oldbury, in the county of Worcester, England, have invented a new, original, and ornamental Design for a Sadiron Cover, of which the following is a specification, reference being had to the accompanying drawing, forming part thereof and in which,

The characteristic features of my design reside in the sadiron cover shown having curvatures in the sides thereof as best shown in Figure 3 of the drawing.

I claim:

The ornamental design for a sadiron cover, substantially as shown and described.

PERCY WILLIAM DAVIS.
